his Attorney.

UNITED STATES PATENT OFFICE.

ORRIN A. HANFORD, OF PASADENA, CALIFORNIA.

PORTABLE HAND TOOL FOR CAPPING, SEALING, AND UNSEALING BOTTLES.

1,422,970.

Specification of Letters Patent. Patented July 18, 1922.

Application filed March 26, 1921. Serial No. 455,734.

To all whom it may concern:

Be it known that I, ORRIN A. HANFORD, a citizen of the United States, residing at Pasadena, in the county of Los Angeles and

5 State of California, have invented certain new and useful Improvements in Portable Hand Tools for Capping, Sealing, and Unsealing Bottles, of which the following is a specification.

10 My invention relates to a portable hand tool for capping, sealing and unsealing the mouth or bead of bottles.

The main object of this invention is to provide simple, durable, economical and thoroughly efficient means adapted to be carried and manipulated in the hand of an operator, whereby an ordinary crown cap is seated on the top of a bottle, and securely attached and sealed to the head of the bottle, and for unsealing and removing the cap from the said bottle.

Another object of the invention is to so construct the novel tool as to include a die member carried by a handle fixedly secured thereto, said die member being provided with means for holding the crown cap on the top of a bottle until the outer upper end portion of the die is struck a sharp blow with a mallet or hammer which will force 25 the die downwardly thereby causing the flaring corrugated flange formed on the said cap to be drawn or compressed around the head formed at the upper end of the bottle, whereby the cap is securely locked and 30 sealed to the top of the bottle.

Another object of the invention is to provide means carried within the die member whereby the tool will be caused to readily release itself from the cap, thus preventing 40 the breaking of the bottle neck.

A further object of the invention is to provide means carried by the tool handle, which may be adjusted and arranged so that its lower forward end will rest beneath the 45 corrugated cap, while the handle serves as a lever for the purpose of releasing or unsealing the cap from the bottle.

The foregoing and such other objects as 50 may appear from the ensuing description are attained by the novel features of construction, arrangement, location and combination of parts hereinafter more fully described, illustrated in the accompanying drawings, and particularly pointed out in the claims, and 55 appended hereto, it being understood that slight changes in the precise form, propor-

tions, and minor details of construction may be resorted to without departing from the spirit or sacrificing any of the advantages of the invention.

60 In the accompanying drawings forming a part of this specification, it will be seen that:

Figure 1 shows in vertical section the crown cap seated on a bottle head with the tool embodying my invention above it and 65 resting thereon.

Figure 2 is a similar view showing the cap and tool as they appear upon the bottle at the conclusion of the capping and sealing operation, and Figure 3 is an elevation 70 showing the position assumed by the tool when it is desired to remove or unseal the cap from the bottle head.

Similar numerals of reference are employed to designate like parts throughout the 75 several views of the drawings.

In the embodiment of my invention as illustrated, and which shows a preferred construction, the numeral 1 indicates the crown of the cap, 2 the skirt and 3 the annular flaring corrugated flange formed integral with the crown cap.

The numeral 4 designates the die member of my improved tool, said die being preferably formed of sheet steel, or other suitable 85 sheet metal possessing the desired strength, and provided with an inner annular wall which is tapered or beveled from its bottom edge upwardly and inwardly at 5, said wall then extending vertically upward and terminating with a horizontal inner solid top wall 6, thereby forming a chamber within said die member for the reception of a hollow annular slid able capping member 7, formed preferably of sheet metal of the re- 90

quired strength, the outer wall of said member 7 being adapted to slidably engage with the inner wall of the die member, the lower end portion 8 of the member 7 being adapted to contact with the upper surface of the 100 crown cap, while the upper flat surface 9 of the member 7 contacts with the lower surface of a metallic plate washer 10, said washer serving the dual purpose of protecting the soft rubber gasket 11, arranged in 105 contact with the upper face of said washer and the inner top surface of the die member, and to strengthen the walls of said die member when subjected to a blow with a hammer or mallet for forcing the crown cap on 110 the bottle head.

The body portion of the die member is

formed with an elongated slot 12 there-through for the reception of the inner terminal end portion 13 of a resilient handle member 14, said end portion 13 passing through an opening formed in the annular upright wall 15 of the member 7, and said slot 12 permitting a limited reciprocating movement of the said member 7.

The handle member 14 is formed of a single piece of solid wire possessing sufficient strength for the purposes required, one end portion 16 of its arm 17, being preferably reduced and fixedly confined and secured within the beaded lower end portion 17' of the die member, while its upper resilient arm 18 is provided with the reduced end portion 13 which passes through the elongated slot 12 and the opening formed in the member 7.

20 In Fig. 1, the device is illustrated as it appears on the top of a bottle before the sealing operation is performed, and showing the crown cap held on the top of the bottle with the lower surface of the member 7 resting thereon and the lower inner beveled portion of the die member in contact with the skirt of the cap, thus when a sharp blow is imparted by a suitable mallet or hammer to the upper outer surface of the die member with sufficient force, said die member is forced downwardly and carried to assume the position shown in Fig. 2 thereby forcing the member 7 to slide upwardly causing the soft rubber gasket to be compressed between 30 the washer plate and the top of the die member, and at the same time forcing the lower portion of the die member, which is in contact with the skirt portion of the cap, downwardly thus forcing the flaring corrugated portion of the cap inwardly around the bottom or lower portion of the annular bead formed around the outer top portion of the bottle neck 19, thereby capping and tightly sealing the mouth or top of said bottle.

45 Carried by and connected to the arms of the handle member is a slidable metallic catch 20, the lower front portion of which is preferably provided with an integral extended tongue 21 adapted to rest beneath the corrugated extensions formed around the lower edge of the skirt of the crown cap when said slide 20 is adjusted to the position shown in Fig. 3, so that when it is desired to unseal or remove the crown cap it will be 55 simply necessary to lift upwardly on the handle member, which serves as a lever, thereby lifting the crown cap from its sealed position as will be readily apparent.

It will be seen that my novel means may 60 be easily and readily manipulated in the hand of an operator for both sealing and unsealing a crown cap, without requiring the use of expensive machinery, and that the several parts constituting the novel device 65 may be made of any suitable or desirable

material adequately adapted to perform the desired and required functions.

It will be perceived that when the die member is forced to the position shown in Fig. 2, the soft rubber gasket will be compressed, hence the reaction thereof will have a tendency to readily release said die member from contact with the cap and avoid the breaking of the bottle neck or top portion thereof.

Having thus described my invention what I claim and desire to secure by Letters Patent is:—

1. A portable hand tool of the character described, comprising a chambered die member provided with a beaded lower end, a slidable member within the die member, a washer plate within said first named member, resilient means adapted to contact with the upper surface of said washer plate, and a handle member with one end fixedly secured to the beaded portion of the die member and its other end passing through an opening formed in the body of the said slid- 80 able member.

2. A portable hand tool of the character described, comprising a die member having an inner tapered and vertical wall, a slidable member adapted to contact with said vertical walls, and a resilient handle member with 90 one end fixedly secured to the lower end of the die member and its other end projecting through an elongated slot formed in the wall of the die member and passing through an opening formed in the body of the said 100 slid-able member.

3. A portable hand tool of the character described, comprising a die member provided with a beaded portion at its lower end and an elongated slot formed through its body, a hollow slidable member adapted to engage the inner wall of said die member and having an opening through its body portion, a washer plate fitted within said die member, resilient means adapted to contact 110 with the upper surface of said washer plate and the inner surface of the top of the die member, and a handle with one end fixedly secured within said beaded portion and its other end passing through said opening 115 formed in the body portion of the slid-able member.

4. A portable hand tool of the character described, comprising a die member formed with a beaded portion at its lower end, a hollow slidable member fitted within said member, and a handle member having one end thereof fixedly secured to said beaded portion and its other end passing through an opening formed in the body of said slid- 120 able member.

5. A portable hand tool of the character described, comprising a die member formed with a beaded portion at its lower end, a slid-able member fitted within said die mem- 130

ber, a washer plate fitted within the die member, resilient means disposed between said washer plate and the upper end of the die member, a resilient handle formed with one end fixedly secured to the beaded portion of the die member and its other movable end passing through an opening formed

in the body of said slidable member, and means overlapping the handle and slidably connected thereto adapted to be adjusted beneath a crown cap whereby the said cap is removed by the upward movement of said handle.

ORRIN A. HANFORD.
